UNITED STATES PATENT OFFICE.

WILLIAM MASON, OF HARTFORD, CONNECTICUT, ASSIGNOR TO THE COLTS PATENT FIRE-ARMS MANUFACTURING COMPANY, OF SAME PLACE.

BREECH-LOADING FIRE-ARM.

SPECIFICATION forming part of Letters Patent No. 247,376, dated September 20, 1881.

Application filed May 21, 1881. (No model.)

To all whom it may concern:

Be it known that I, WM. MASON, of Hartford, in the county of Hartford and State of Connecticut, have invented a new Improvement in Breech-Loading Fire-Arms; and I do hereby declare the following, when taken in connection with the accompanying drawings, and the letters of reference marked thereon, to be a full, clear, and exact description of the same, and which said drawings constitute part of this specification, and represent, in—

Figure 1, a sectional side view of the parts in their normal condition; Fig. 2, the same with the barrel tilted; Fig. 3, a modification.

This invention relates to an improvement in that class of arms in which the barrel or barrels are hung forward and so that the breech end tips up to open the cartridge-chamber, and known as "barrel tilting up at the breech," and with special reference to what are known as "concealed hammers"—that is to say, the hammer arranged within the receiver of the arm and cocked in the act of tilting the barrels.

The invention consists in a rock-shaft arranged beneath the barrels transversely there-to, and substantially the axis upon which the barrels turn, and in connection with the barrel, so that as the barrels are tilted the rock-shaft will turn upon its axis, combined with a main-spring hung to said shaft, its doubled end hung to said shaft, the other two ends hinged to the hammer respectively, the one in front and the other in rear of the pivot, as more fully hereinafter described.

35 A represents the frame of the receiver, extending forward beneath the barrels B, as at C, the forward end rounded to receive the fore-arm D, in substantially the usual manner. In a recess in the receiver the hammer E is hung upon a pivot, *a*, the upper end or nose arranged to strike a firing-pin, *b*; or it may be constructed with a projection which will pass through an opening in the breech end of the receiver to strike the primer.

45 F is a transverse rock-shaft arranged at the forward end of the receiver, beneath the barrel, and forming substantially the axis on which the barrels turn in tilting. On the said rock-shaft a cam-like projection, *f'*, is formed upon

below, and on the under side of the barrel a projecting lug, *l*, is formed to hook over the rock-shaft, its front surface engaging the cams *f'* *h'*, as shown, so that when the barrels are tilted the surface of the lug above the pivot 55 bears against the cam *f'* and turns the rock-shaft forward. Then, in returning the barrels, the surface of the lug on the other side bears upon the cam *h'* and turns the rock-shaft in the opposite direction.

In the best adaptation of this invention a bell-crank lever is hung in rear of the shaft F upon a pivot, *d*, one arm, *e*, entering a recess on the rear surface of the shaft, the other arm, *f*, extending upward, and to this upper arm 65 the doubled end of the V-shaped mainspring is hung, as upon a pivot, *h*, the two ends of the mainspring extending toward the hammer, one end, *i*, hung to the hammer forward of its pivot, as at *l*, the other end, *m*, of the mainspring hung 70 to the hammer in rear of the pivot, as at *n*, the connection between the hammer and the respective ends of the mainspring being by the common and well-known link, *s*, and strut *t*.

When the barrels are tilted, as in Fig. 2, the 75 rock-shaft F moves from the position denoted in Fig. 1 to that denoted in Fig. 2, throwing up the arm *e* of the bell-crank lever and turning the other arm, *f*, to the rear toward the hammer. In this movement of the lever the main-spring acts as a connection to the hammer to impart the movement of the lever to the hammer—that is, pressing it backward—the lower end, *i*, of the mainspring bearing against the hammer above the pivot, as at *r*, which forces 80 the hammer to full-cock, where it is engaged by the sear H. In the act of cocking the hammer the two ends of the mainspring are carried rearward, the pivot *n*, to which the end *m* of the mainspring is attached, being in rear of 85 the hammer-pivot, is carried downward, and the point *l*, to which the end *i* of the mainspring is attached, or upon which it bears, being forward of the hammer-pivot, is raised with the end of the mainspring—that is, in cocking the 90 hammer the two ends of the mainspring are brought together, as seen in Fig. 2. Then when the barrels are returned, leaving the hammer at full-cock, the lever is also returned, which 95 draws the mainspring forward, as indicated in 100

broken lines, Fig. 2. The link-connections between the mainspring and the hammer are brought from their rearward inclined position to nearly a perpendicular, so that the end *m* of the mainspring is drawn downward, while the other end, *i*, is raised, as also shown in broken lines, Fig. 2, bringing the two ends of the spring still nearer together, which completes the application of the power of the mainspring to the hammer, and which, it will be observed, is applied partially in tilting the barrels and completed in their return.

While I prefer the bell-crank lever, the forward end of the mainspring may be hung directly to the shaft below its center, as seen in Fig. 3, so that from the rotation of the shaft the spring will receive substantially the same movement as imparted by the lever, and act upon the hammer in the same manner. I therefore do not wish to limit the invention to the employment of the lever.

It will be understood by those skilled in the art that, while specially intended for double-barreled arms, this invention may be applied to single-barrel arms.

In another application for patent, which I have entitled "Case A," I have shown the rock-shaft arranged in the same manner as in this application, but with a different intermediate mechanism. I therefore do not in this application make broad claim to the transverse rock-shaft rotated by the opening and closing movements of the barrel to cock the hammer; but

What I do claim is—

35 1. In fire-arms in which the breech is opened

by the barrel tilting up at the breech, the combination therewith of a transverse rock-shaft arranged substantially at the axis upon which the barrels turn, an extension from the barrels into connection with said rock-shaft, so that as 40 the barrels are tilted said shaft will be turned, a hammer hung at the rear with a V-shaped mainspring, and mechanism, substantially such as described, to connect the doubled end of said mainspring with the shaft, so that as the shaft 45 is rotated by tilting the barrels the said spring is forced to the rear and returned as the barrels are closed, the two ends of the mainspring hung to the hammer, the one forward of the hammer-pivot, the other in rear of said pivot, 50 substantially as described.

2. In fire-arms in which the breech is opened by the barrel tilting up at the breech, the combination therewith of a transverse rock-shaft arranged substantially at the axis upon which 55 the barrels turn, an extension from the barrels into connection with said rock-shaft, so that as the barrels are tilted said shaft will be turned, a hammer hung at the rear with a bell-crank lever, one arm of which engages with said rock-shaft, a V-shaped mainspring hung by its doubled end to the other arm of said lever, the two ends of the spring hung to the hammer respectively, the one forward of, the other in rear of, the pivot upon which the hammer turns, 60 substantially as described.

WILLIAM MASON.
